UNITED STATES PATENT OFFICE.

FRANK E. FEY, OF SEATTLE, WASHINGTON, ASSIGNOR OF ONE-HALF TO EUGENE A. BALSLEY, OF CHICAGO, ILLINOIS.

CONTAINER.

Application filed February 13, 1922. Serial No. 536,323.

To all whom it may concern:

Be it known that I, FRANK E. FEY, a citizen of the United States, and resident of Seattle, in the county of King and State of

5 Washington, have invented certain new and useful Improvements in Containers, of which the following is a full, clear, concise, and exact description, reference being had to the accompanying drawings, forming a 10 part of this specification.

My invention relates to improvements in containers, and is particularly concerned with, though not limited to, improvements in stamped or pressed metal containers.

15 The objects of my invention are,

First, to provide a container comprising two sections which are so shaped that a plurality of said sections can be nested in each other so that they will require but very 20 little space for shipment;

Second, to provide a container of the class described which comprises means whereby the two sections can be easily and quickly taken apart for the purpose of cleaning the 25 inside walls, and also easily and quickly secured together in fluid tight relation;

Third, to provide a container comprising means for protecting from injury the means which are used for securing the two sections 30 together;

Fourth, to provide a container of the character described comprising means for preventing the nested sections from wedging into each other;

35 Fifth, to provide a container having a pair of spaced rings entirely surrounding it, which act as rollers upon which the container can be rolled from place to place, and

Finally, to provide a container of the character described which is simple in construction, rugged, and economical to manufacture.

Other objects will appear as this description progresses, reference being had to the 45 accompanying drawings in which—

Figure 1 is a side elevation of one embodiment of my invention;

Figure 2 is a side elevation of a plurality of nested sections, parts of which are shown 50 in section;

Figure 3 is a transverse section taken on line 3—3 of Figure 1, and

Figure 4 is a detail section taken on line 4—4 of Figure 3.

Throughout the several views, similar ref-

erence characters will be used for referring to similar parts, and the several sections are taken looking in the directions of the small arrows.

Referring now to the drawings, my improved container comprises the two half sections 5, the adjacent ends of which are open, and the remote ends of which are provided with the closures 6 which are preferably cupped inwardly, as shown in Figure 2, to provide the re-inforcing beads 7.

From an inspection of Figures 1 and 2, it will be noted that the sections taper gradually from their open ends to their closed end, thereby providing a construction which permits a plurality of the sections to be nested, as shown in Figure 2. A cam ring 8 is secured to each section adjacent its open end by electric welding, as shown at 9 and 10, or any other suitable manner. A plurality of lugs 11 extend outwardly from each of said cam rings and project toward the other section, as shown in Figures 3 and 4. When the two sections are assembled, as shown in these figures, as well as in Figure 1, the lugs of one section project between the lugs of the other section. The surfaces 12 of the lugs 11 are beveled to form an interrupted outwardly flaring annular channel extending around the container.

To clamp the two sections of the container together, I provide the locking ring 13 which has an inwardly extending beveled rib 14 which fits into the annular channel just referred to. The ring 13 is made in the form of a split ring to facilitate its application to the container, and its two ends are joined by a right and left hand threaded bolt 15, the opposite ends of which coact with the threaded lugs 16 on the ends of the ring 13. By turning the screw 15 in the proper direction, the two ends of the ring can be drawn together, thereby forcing the rib 14 inwardly in the channel formed by the surfaces 12 of the lugs, thus drawing the two sections of the container toward each other and clamping the gasket 17 between the adjacent ends of the container to form a liquid-tight joint.

To protect the barrel itself, and also the joint-forming means just described from injury when the barrel is rolled from place to place, I provide the two spaced guard rings 18 which are preferably formed of angle iron and secured to each section ad-

jacent the cam ring of that section. The outwardly extending flanges of these guard rings project beyond the clamping means and protect them from mechanical injury 5 when the container is rolled along. These guard rings also provide means for preventing the sections from wedging or jamming in each other when they are nested, as shown in Figure 2. From an examination of this 10 figure, it will be noted that the guard ring 18 of an upper section rests upon the outer ends of the lugs 11 of the next lower section, thereby limiting the extent to which one section can be inserted in another. The 15 guard rings 18 are placed at such a distance from the open end of each section that when the sections are nested, as shown in Figure 2, there is no wedging action of one section in the surrounding section.

20 From the above description, it will be clear that I have provided a container which can be separated into sections so constructed that they can be nested into each other so as to require a minimum amount 25 of space for shipment, and that such container comprises means for easily and quickly clamping the two sections of a container to each other in fluidtight relation, and that suitable means are provided for 30 protecting the clamping means from mechanical injury, these same means acting as rolling surfaces upon which the container can be rolled.

35 While I have described the details of construction of one embodiment of my invention, it is to be clearly understood that my invention is not limited to this particular embodiment, but is capable of other adaptations and modifications within the scope of 40 the appended claims.

Having thus described my invention, what I claim is:

1. A stamped metal container comprising 45 two sections, the adjacent ends of which are open and the remote ends of which are closed, said sections tapering toward their closed ends, a ring surrounding each section adjacent its open end and provided with spaced outwardly extending lugs projecting 50 toward the other section, the lugs of one section projecting between the lugs of the other section, the lugs of said sections having beveled faces coacting to form an interrupted outwardly flaring annular channel extending around said container, a split locking ring having a beveled rib extending into 55 said annular channel, means for tightening said ring to draw said sections toward each other, a gasket confined between the adjacent ends of said sections, and an annular guard ring surrounding each section adjacent the cam ring of said section and projecting outwardly beyond said cam ring.

2. A stamped metal container comprising 60 two sections, the adjacent ends of which

are open and the remote ends of which are closed, said sections tapering toward their closed ends, a ring surrounding each section adjacent its open end and provided with spaced outwardly extending lugs projecting 70 toward the other section, the lugs of one section projecting between the lugs of the other section, the lugs of said sections having beveled faces coacting to form an interrupted outwardly flaring annular channel extending around said container, a split locking ring having a beveled rib extending into 75 said annular channel, means for tightening said ring to draw said sections toward each other, and a gasket confined between the adjacent ends of said sections.

3. A container comprising two sections, the adjacent ends of which are open and the remote ends of which are closed, a ring 80 surrounding each section adjacent its open end and provided with spaced outwardly extending lugs projecting toward the other section, the lugs of one section projecting between the lugs of the other section, the lugs of said sections having beveled faces 85 coacting to form an annular channel extending around said container, a split locking ring having a beveled rib extending into said annular channel, means for tightening said ring to draw said sections toward each other, and a gasket confined between the adjacent ends of said sections.

4. A container comprising two sections, the adjacent ends of which are open, and the remote ends of which are closed, a gasket 100 confined between the adjacent ends of said sections, a locking ring, coacting means on said locking ring and said sections for drawing said sections toward each other, and guard rings one on each of said sections and projecting outwardly beyond said locking ring.

5. A container including two sections, the adjacent ends of which are open, each section being provided at its edge adjacent to 110 its open end with outwardly extending lugs, the lugs of one section being arranged between the lugs of the other section, and a clamping ring arranged between the lugs of said sections respectively.

6. A container including two sections, the adjacent ends of which are open, each section being provided at its edge adjacent to its open end with outwardly extending lugs, the lugs of one section being arranged to project between and beyond the lugs of the other section so as to form an annular groove therebetween, and a clamping ring arranged within said groove.

7. A container including two sections, the adjacent ends of which are open, each section being provided at its edge adjacent to its open end with outwardly extending lugs provided with cam surfaces positioned beyond the edge of its section of said con-

tainer, and a clamping ring arranged to engage the opposed cam surfaces of said lugs.

8. A container comprising two sections, the adjacent ends of which are open, a locking ring, co-acting means on said locking ring and said sections, for drawing said sections toward each other, and guard rings, one on each of said sections and projecting outwardly beyond said locking ring.

10. 9. A container, comprising two sections, the adjacent ends of which are open, a locking ring, co-acting means on said locking ring and said sections, for drawing said sec-

tions toward each other, and guard rings, one on each of said sections and projecting outwardly beyond said locking ring, each of said guard rings comprising a strip of angle iron having one flange engaging said container, and the other flange projecting outwardly therefrom.

In witness whereof, I hereunto subscribe my name this 19th day of January, 1922.

FRANK E. FEY.
